CLAIM

The ornamental design for a finger tip oximeter, as shown and described.

DESCRIPTION

FIG. 1 is a perspective view of a finger tip oximeter showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines in the figure views are included for the purpose of illustrating portions of the finger tip oximeter that form no part of the claimed design.
